Application June 27, 1936, Serial No. 63,539

To all whom it may concern:

Be it known that I, Charles R. Kovar, a citizen
of the United States, residing at 102-32 Park Lane
South, Richmond Hill, Long Island, in the city of
New York, county of Queens, and State of New
York, have invented a new, original, and orna-

is a specification, reference being had to the ac-
companying drawing, forming part thereof.

Figures 1 and 2 are respectively a front view
and a back view of a glove embodying my new
design.

The entire glove is of ribbed fabric of the tex-
ture shown in the drawing. A mock seam ex-
tends substantially the entire length of the back,
and light-reflecting ornaments are attached to
the glove along said seam and at the edge of the
cuff, as shown in Figure 2.

I claim:

The ornamental design for a glove, as shown
and described.
